(57) **CLAIM**

The ornamental design of a lamphead for luminaires, as shown and described.

DESCRIPTION

FIG. 1 is a perspective view illustrating a first embodiment of the invention in a use environment with a portion of a luminaire to which the lamphead is fitted being shown in phantom;

FIG. 2 is a front elevational view of the lamphead of the invention;

FIG. 3 is a side elevational view of the lamphead of the invention with portions thereof which are not part of the invention being shown in broken lines;

FIG. 4 is a side elevational view of the lamphead of the invention shown rotated 90° from the view of FIG. 3;

FIG. 5 is a side elevational view shown rotated 180° from the view of FIG. 4;

FIG. 6 is a back view of the lamphead;

FIG. 7 is a perspective view of a second embodiment of the invention in a use environment with a portion of a luminaire to which the lamphead is fitted being shown in phantom;

FIG. 8 is a front elevational view of the lamphead of the invention;

FIG. 9 is a side elevational view of the lamphead of the invention with portions thereof which are not part of the invention being shown in broken lines;

FIG. 10 is a side elevational view of the lamphead of the invention shown rotated 90° from the view of FIG. 9;

FIG. 11 is a side elevational view shown rotated 180° from the view of FIG. 10; and,

FIG. 12 is a back view of the lamphead.
